ASA R. REYNOLDS, OF AUBURN, NEW YORK.

Letters Patent No. 61,759, dated February 5, 1867.

IMPROVEMENT IN SHAFT COUPLINGS FOR CARRIAGES.

The Schedule referred to in these Letters Patent and making part of the same.

TO ALL WHOM IT MAY CONCERN:

Be it known that I, ASA R. REYNOLDS, of Auburn, in the county of Cayuga, and State of New York, have invented certain new and useful Improvements in Shaft Couplings for Carriages and other purposes; and I do hereby declare the following to be a full, clear, and exact description of the same, reference being had to the accompanying drawings, making a part of this specification, in which—

Figure 1 represents one of the couplings in question; and

Figures 2 and 3 represent modifications of the same, though embracing the same general characteristics.

Similar letters of reference, where they occur in the separate figures, denote like parts in all the drawings.

My invention relates to a shaft coupling of simple construction, easily adjusted to take up the wear, and prevent rattling or noise, and protected in a great degree from dirt or grit, which wears away the metal.

To enable others skilled in the art to make and use my invention, I will proceed to describe the same with reference to the drawings.

A may represent the axle of a carriage or other piece to which the shaft B is attached. The bow or clip C on the axle is secured by a plate or washer, *a*, and nuts *b b*. On the forward part of the clip or band C there is wrought a loop, *c*, to which the shaft B is hinged or attached as follows: the shaft iron *d* has a half bow, *e*, wrought upon it which catches over the bar of the loop *c*, which bar, though wrought solid with and a part of the loop and clip, corresponds to the ordinary bolt used for shaft couplings, but without any of the disadvantages of such bolt. Underneath the shaft iron *d*, and bolted to it by a jam or set-nut, *k*; and bolt *f*, is another piece of metal, *g*, which is so formed as to bear against the shaft iron at its front end *h*, and against the bar or bolt in the loop *c*, at its rear end *i*. At the points intermediate between these bearing points there is a space, *n*, sufficient to admit of the taking up of all wear or shackle between the shaft iron and the loop or part to which it is hinged. Thus the shaft can be raised or lowered by its connection, and all rattling, shackle, or noise avoided. The bow *e* of the shaft iron covers the joint between itself and the under bar, and also of the piece *g*, so that dirt and grit cannot work into or between the moving parts and the bar, which would cause them to cut and wear. If the shaft coupling becomes loose it is only necessary to turn the bolt *f*, the screw-thread on which takes into the female screw in the piece *g*, and then run up the jam-nut *k*, to keep the bolt from turning. As the screw-bolt *f* enters the piece *g* at a point intermediate between its bearing points *h i*, the force of the bolt may put a slight spring into the piece *g*, so that this spring pressure may act to keep it constantly against the bar or bolt in the loop *c*. If it be too tight, the jam-nut may be slackened up and the screw-bolt turned the opposite way. In figs. 2 and 3, instead of the piece to which or on which the loop *c* is worked or wrought being formed into a clip or bow, it is left straight, so as to be fastened to any straight piece. In fig. 2, the loop *c* projects at right angles to the piece C, whilst in fig. 3 it is wrought upon its ends. These modifications are obvious where the piece or part to which the shaft is to be attached has a flat or plain surface instead of a curved one. In these modifications, instead of a screw-bolt and jam-nut, I have shown a screw-bolt which is the equivalent of the bolt *f*, fig. 1, and a set-bolt, *m*, which makes a fulcrum for the screw-bolt *f* to work against. The same spring pressure can be put into the pieces *g* by these two bolts, as by the plan shown in fig. 1, and the joint made tight or loose by the turning of the screw-bolt, as the case may be. In these modifications the same protection is given to the joints to prevent dirt, mud, and grit from working into them. And in these cases, as in fig. 1, the draw-bar or bolt in the loops is wrought out of the solid metal with the pieces C.

Having thus fully described my invention, what I claim therein as new, and desire to secure by Letters Patent, is—

A shaft coupling composed of a loop-bar or bolt, wrought in one and the same piece with the loop and strap, an under and upper piece fitting over or against it, and a tightening bolt controlling said under and upper piece, to adjust their frictional contact with the loop or draw-bar or bolt, substantially as and for the purpose described.

ASA R. REYNOLDS.
